UNITED STATES PATENT OFFICE.

SILAS A. MANUEL AND JULIAN R. NOTTINGHAM, OF WASHINGTON, DISTRICT OF COLUMBIA, ASSIGNORS OF ONE-FOURTH TO RICHARD J. EARNSHAW, OF WASHINGTON, DISTRICT OF COLUMBIA.

REVOLVING BOOK-SUPPORTER.

SPECIFICATION forming part of Letters Patent No. 700,523, dated May 20, 1902.

Application filed February 25, 1902. Serial No. 95,550. (No model.)

To all whom it may concern:

Be it known that we, SILAS A. MANUEL and JULIAN R. NOTTINGHAM, citizens of the United States, residing at Washington, in the 5 District of Columbia, have invented certain new and useful Improvements in Revolving Book-Supporters; and we do hereby declare the following to be a full, clear, and exact description of the invention, such as will enable others skilled in the art to which it 10 pertains to make and use the same.

Our invention relates in general to a revolving book supporter or holder, but more particularly to certain novel features of adjustability by means of which different sizes 15 of books may be supported and held in open position, with their leaves protected from injury incident to the frequent handling in using the book; and it consists, essentially, of 20 the peculiar construction and novel arrangement of the various parts, as will be herein-after fully described, and particularly stated in the claims.

The invention is especially designed to support and hold a "hotel-register," although it 25 will be evident that the device is equally applicable for supporting and holding other books that require when in use to be turned about, and one of the principal objects of the 30 invention is to produce a device of this character of the simplest and cheapest form consistent with durability and effectiveness in use.

Other objects of the invention, such as providing adjustable means to accommodate the 35 support to different-size books, will become apparent upon a further description thereof.

In the drawings, Figure 1 is a top plan view 40 of our improved book-supporter, showing a book in dotted lines supported thereon; Fig. 2, a side elevation; Fig. 3, a central transverse section; Fig. 4, a perspective view of one of the extensible slides and leaf-holding attachments; Fig. 5, a modified form of the leaf-holding attachment, and Fig. 6 a modified form of extensible slide and slidable leaf-holder.

In the several views the letter *a* indicates a suitable base provided with a central aperture *a'*, in which is journaled the arm *b* of the 50 book-rest *b'*. The book-rest preferably con-

sists of two leaves or plates *b*², separated a sufficient distance apart to form a depression *b*³ for the reception of the back of the book to be supported and joined together by connecting-pieces *b*⁴, preferably cast integral 55 with the leaves or plates *b*², the central connecting-piece being provided with the journal arm or pivot *b*. The book-rest *b'* is mounted upon the base in an inclined position, as shown in Fig. 2, in order to support the book 60 in the most convenient position for writing, and in order to adapt the device for supporting different sizes of books we provide each leaf *b*², preferably the under surface, with upper and lower transverse guideways *b*⁵, in 65 which operate the arms *c* of an extensible slide *c'*. Each slide *c'* is provided with a rectangular bore, and slidably in each end of each slide is a rod or arm *c*³, carrying a leaf-holding arm *c*³, said arm *c*³ being adapted to 70 press upon the leaves, at the corners thereof, and hold said leaves down with a spring-pressure. While it is preferred to make the bore of the slide *c'* rectangular and the rod *c* to correspond therewith, so as to prevent said 75 rod turning in the slide, the same object may be accomplished by making both the bore of the slide and the rod round and providing said rod with a pin adapted to project through a longitudinal slot in said slide, the slot being 80 of sufficient length to allow for a proper extension of the leaf-holder.

In operation the book is placed upon the support with the back in the depression between the leaves *b*², bringing the covers of 85 the book flat upon said leaves. The leaf-holders are then placed in position to rest upon the leaves of the book at the respective corners thereof. As thus supported the book is held in open position, with the corners of 90 the leaves protected from injury.

When it is desired to turn the leaves of the hotel-register or other book, all that is required to be done is to remove the leaf-holders, which is accomplished by pulling out the 95 rod *c*³, carrying said leaf-holders. Where large books are to be supported, the slides *c'* are adjusted by pulling them out a distance sufficient to permit the leaf-holders to engage the leaves of the book at its corners, they be- 100

ing the most desirable points at which to hold down the leaves, as writing in the book will not be interfered with thereby.

The adjustable feature of the two lower leaf-holders may be obtained by other means than the slidable rod c^2 —such, for instance, as pivoting the leaf-holders directly upon the ends of the slides c' , as shown in Fig. 5. When thus constructed, they may be readily moved to clamp the leaves and be removed therefrom, as the lower edge of the book is always flush with the corresponding edge of the supporter; but to provide for increased length of books it will of course be necessary to employ the extensible leaf-holder at the upper part of the supporter.

The book-rest b' may be either constructed of cast or sheet metal, but if constructed of the latter metal a depression of sufficient width must be made in the center to accommodate or receive the back of the book. If desired, the book-rest may be materially lightened by casting or stamping it in skeleton form.

25 Other forms of leaf-holding arms which exert a constant pressure may be employed without sacrificing the principle of our invention or departing from the scope thereof.

The device being especially adapted for supporting hotel-registers the many advantages of our invention will be readily apparent and duly appreciated by those having need for its use, as access can be had to the register from both sides of the counter.

35 Having thus fully described our invention, what we claim as new, and desire to secure by Letters Patent, is—

1. In a book-holder, the combination with a suitable base, of a rest for the book, an extensible slide at each side of the rest, to adapt it to books of different widths, and means carried by the extensible slides for clamping the leaves at the corners thereof, said means being adjustable transversely to 45 said slides.

2. In a book-holder, the combination with a suitable base, of a rest for the book, an extensible slide at each side of the rest, and spring leaf-clamping devices, carried by the extensible slides and adjustable transversely thereto. 50

3. In a book-holder, the combination with a suitable base, of a rest for the book, an extensible slide at each side of the rest, an adjustable leaf-clamping device slidably in the upper end of each extensible slide, and a leaf-clamping device carried at the lower end of each extensible slide. 55

4. In a book-holder, the combination with a suitable base, of a rest for the book, an extensible slide at each side of the rest, and an adjustable leaf-clamping device slidably in the upper and lower end of each extensible slide, whereby books of different lengths may be supported, and the lower 65 edge of the book brought close to the surface of the object upon which the device is placed.

5. In a book-holder, the combination with a suitable base, of a rest for the book, an extensible slide at each side of the rest, 70 said slides consisting of a rectangularly-bored tube provided with arms adapted to slide in guideways on the rest, and leaf-clamping devices carried by the extensible slides and adjustable transversely thereto. 75

6. In a book-holder, the combination with a suitable base, of a rest for the book, an extensible slide at each side of the rest, said slides consisting of a rectangularly-bored tube having arms adapted to slide in guideways on the rest, and spring leaf-clamping devices having arms slidable in the ends of the extensible slides. 80

In testimony whereof we affix our signatures in the presence of two witnesses.

SILAS A. MANUEL.

JULIAN R. NOTTINGHAM.
